Primary Examiner — Catherine S Posthauer*Assistant Examiner* — Alison M Ofstun(74) *Attorney, Agent, or Firm* — Wolf, Greenfield & Sacks, P.C.(57) **CLAIM**

The ornamental design for a battery pack for a camera, as shown and described.

DESCRIPTION

FIG. 1 is a front perspective view of a battery pack for a camera showing my new design;

FIG. 2 is a front view thereof;

FIG. 3 is a rear view thereof;

FIG. 4 is a top plan view thereof;

FIG. 5 is a right side view thereof;

FIG. 6 is a left side view thereof; and,

FIG. 7 is an enlarged view thereof, portion "7" shown in FIG. 1.

In the drawings, the dash-dash broken lines illustrate portions of the battery pack for a camera which form no part of the claimed design. The dash-dotted lines illustrate a boundary of the claimed design, and enlarged view indicator and form no part thereof.
